UNITED STATES PATENT OFFICE.

ANDREW J. CARMICHAEL AND ALBERT M. WUNDERLICH, OF NEW HAVEN, CONNECTICUT, ASSIGNORS TO THE GREIST MANUFACTURING COMPANY, A CORPORATION OF CONNECTICUT.

SEWING-MACHINE BRAIDER OR CORDER.

Application filed July 9, 1927. Serial No. 204,519.

This invention has for its object to provide a convenient sewing machine braider or corder in which the braid or cord passage is adjustable so as to accommodate braids or 5 cords of different widths or sizes and also comprises laterally adjustable means for engaging a braid or cord already stitched to the work so as to guide the work parallel to said stitched braid or cord in stitching several 10 rows of braids or cords, thus enabling the rows of braids or cords to be located at any desired distance apart, all as will hereinafter more fully appear.

In the accompanying drawing Fig. 1 is a 15 plan view of the improved braider or corder. Fig. 2 is a side view of the same looking from the left of Fig. 1. Fig. 3 is a front edge view of the same looking from the bottom of Fig. 1. Fig. 4 is a detail plan view of the presser 20 foot part of the attachment and its laterally supporting arm. Fig. 5 is a detail plan view of the adjustable guiding member for the braid or cord already stitched to the work.

Referring to the drawings, 12 denotes a 25 sewing machine presser foot having a shank 13 by which it may be secured to the presser bar of a sewing machine and having a lateral arm 14 which supports the adjustable guiding members. Mounted on the arm 14 is a 30 plate 15 extending laterally of the attachment and provided at its left end with a rearwardly extending guide 16 herein shown as being constructed in the form of a trough comprising two depending lips 17. The plate 15 is a 35 provided with a slot 18 through which passes the lower end or shank of a set screw 19 and which slot also receives the body of a rivet 20 for steadyng the said plate 15 in its different lateral positions of adjustment.

Overlying the plate 15 is a second plate 21 40 having a slot 22 which also receives the shank of the set screw 19 and the body of the rivet 20, thus providing for the lateral adjustment of the said plate 21. The plate 21 carries a down-turned guiding arm 23 which extends 45 rearwardly parallel to the presser foot 12, said arm having a horizontally extending finger 24. The braid or cord to be attached to the work is guided in the space or passage between the arm 23 and the left hand edge of the presser foot and beneath the finger 24, this 50 cord or braid passage between the said arm and presser foot being adjustable in width, to accommodate braids or cords of different

widths or sizes, by adjusting the plate 21 to 55 different lateral positions; this adjustment being conveniently effected, when the set screw 19 is loosened, by means of an upturned lug 25 at the left hand end of the said plate 21. The position of the needle of the machine 60 is indicated by the notch 26 in the right hand edge of the presser foot 12.

After the braid or cord has been stitched to the work the latter will be guided parallel to the said stitched braid or cord in stitching a 65 second braid or cord to the work, by the engagement with the stitched braid or cord by the trough-like guide 16; or, if desired, the work may be guided by positioning the work in such a manner that the stitched braid or 70 cord will occupy the space between the left hand edge of the presser foot and the right hand depending lip 17 of the guide 16.

From the foregoing it will be understood that the improved presser foot braider or 75 corder is formed by three sheet metal parts, so that in manufacturing the attachments these parts may be cheaply made by stamping; while the improved device, by the adjustments afforded by the slotted plates 15 and 21, will 80 accommodate different widths or sizes of braids or cords, and will also enable the latter to be stitched to the work at different distances apart.

Having thus described our invention we 85 claim and desire to secure by Letters Patent:

1. A sewing machine braider or corder composed, aside from a set screw and rivet, of three sheet metal parts only, and comprising adjustable means for guiding the 90 work by a braid or cord already stitched, and adjustable means for guiding braids or cords of different widths or sizes.

2. A sewing machine braider or corder composed, aside from a set screw and rivet, 95 of three sheet metal parts only, and comprising a presser foot having a laterally extending arm, and two plates one of which carries a braid or cord guide and the other a work-guide, both adjustably mounted on said 100 arm.

3. A sewing machine braider or corder composed, aside from a set screw and rivet, of three sheet metal parts only, and comprising a presser foot having a laterally extending arm, a plate carrying a rearwardly extending braid or cord engaging guide adjustably mounted on said arm, and a second 105

adjustable plate having a rearwardly extending braid or cord guiding member also adjustably mounted on said arm.

4. A sewing machine braider or corder comprising a presser foot having a laterally extending arm, a plate carrying a rearwardly extending braid or cord engaging guide adjustably mounted on said arm, and a second adjustable plate having a rearwardly extend-

ing braid or cord guiding member also adjustably mounted on said arm, said braid or cord guiding member being provided with a horizontally extending finger overlying the braid or cord passage.

In testimony whereof we affix our signatures.

ANDREW J. CARMICHAEL.
ALBERT M. WUNDERLICH.
